Primary Examiner—Pamela J. Burgess*(74) Attorney, Agent, or Firm*—Geoffrey A. Mantooth(57) **CLAIM**

The ornamental design for a dog treat of layers of non-ear animal skin folded and pressed into shape of pig ear, as shown and described.

DESCRIPTION

FIG. 1 is a front isometric view of one side of a dog treat of layers of non-ear animal skin folded and pressed into shape of a pig ear showing my new design;

FIG. 2 is a rear elevational view thereof;

FIG. 3 is a right side elevational view thereof;

FIG. 4 is a top plan view thereof;

FIG. 5 is a front elevational view thereof;

FIG. 6 is a bottom plan view thereof; and,

FIG. 7 is a left side elevational view thereof.
